CLAIM

The ornamental design for a paint container, substantially as shown and described.

DESCRIPTION

FIG. 1 is a perspective view of a paint container of the present invention with the lid closed.

FIG. 2 is a plan view of the top of the paint container of FIG. 1.

FIG. 3 is a front view of the paint container.

FIG. 4 is a rear view of the paint container.

FIG. 5 is an end view of the paint container.

FIG. 6 is a plan view of the bottom of the paint container.

FIG. 7 is a perspective view of a variation of the paint container with the lid open.

FIG. 8 is a plan view of the top of the paint container of FIG. 7.

FIG. 9 is a rear view of the paint container of FIG. 7.

FIG. 10 is a front view of the paint container of FIG. 7.

FIG. 11 is a side view of the paint container of FIG. 7; and, FIG. 12 is a plan view of the bottom of the paint container of FIG. 7.
